US00D969128S

(12) **United States Design Patent** (10) **Patent No.:** **US D969,128 S**
(45) **Date of Patent:** **** Nov. 8, 2022**

(54) **SOLID STATE DRIVE MEMORY DEVICE**

(71) Applicant: **SAMSUNG ELECTRONICS CO., LTD.**, Suwon-si (KR)

(72) Inventor: **Hyung-Sup Shim**, Suwon-si (KR)

(73) Assignee: **SAMSUNG ELECTRONICS CO., LTD.**, Suwon-si (KR)

(**) Term: **15 Years**

(21) Appl. No.: **29/758,916**

(22) Filed: **Nov. 19, 2020**

(30) **Foreign Application Priority Data**

Jul. 9, 2020 (KR) 30-2020-0031430

(51) **LOC (13) Cl.** **14-02**

(52) **U.S. Cl.**

USPC **D14/348**

(58) **Field of Classification Search**

USPC D14/167, 172, 204, 300-301, 314, 348, D14/355-358, 363, 365-367, 433-437, D14/480-480.1, 480.7, 484.1; D13/103, D13/107-108, 110, 168-169, 171; D18/11-12

CPC H01L 23/4093; H05K 5/03; H05K 5/04

(57) **CLAIM**

The ornamental design for a solid state drive memory device, as shown and described.

DESCRIPTION

FIG. 1 is a front perspective view of a solid state drive memory device;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a bottom-rear perspective view thereof.

The evenly dashed broken lines in the figures depict portions of the solid state drive memory device that form no part of the claimed design.

1 Claim, 8 Drawing Sheets
